UNITED STATES PATENT OFFICE.

WESTON M. FULTON, OF KNOXVILLE, TENNESSEE, ASSIGNOR TO THE FULTON COMPANY, OF KNOXVILLE, TENNESSEE, A CORPORATION OF MAINE.

INCASED RADIATOR.

1,345,591.

Specification of Letters Patent. Patented July 6, 1920.

Application filed August 31, 1916. Serial No. 117,872.

To all whom it may concern:

Be it known that I, WESTON M. FULTON, a citizen of the United States of America, and a resident of Knoxville, Tennessee, have 5 invented a new and useful Improvement in Incased Radiators, which invention is fully set forth in the following specification.

This invention relates to radiators intended to be inclosed in a casing, and it has 10 for an object to provide such a radiator which, in combination with its casing, will provide a more compact structure than has heretofore been obtained.

It has been proposed, for the purpose of 15 obtaining temperature regulation, to inclose a radiator in a casing, and provide such casing with a damper to regulate the circulation of air past the radiator and therefore the quantity of heated air delivered to the room in which the radiator is positioned. To provide space for the 20 movement of the damper and its operating mechanism, the casing has been made of a size much larger than the radiator, protruding therefrom on at least one side to a considerable distance. Where floor space is limited, this has been a serious objection 25 to the use of an incased radiator. It is an object of this invention to provide an incased radiator that will take up little, if any, more room than the radiator without its casing.

It is sometimes desirable that a passage or passages be provided in the casing of 30 a radiator to direct the current of air in a predetermined path for the purpose of acting upon thermosensitive means controlling a damper. Such an apparatus is illustrated, for example, in my reissued Patent 35 No. 14,309, granted June 5, 1917. It is a further object of this invention to economically provide for such a passage within a radiator casing by the employment of means upon a section of the radiator whereby 40 such section will itself constitute a partition within the casing.

To the end of providing a more compact structure in an incased radiator, the radiator is so constructed as to provide a recess 45 for the reception of the damper of the casing. To the end that a section of the radiator may constitute a partition within the casing, such section is provided with a rib of such dimensions as to contact the wall 55 or walls of the casing.

The invention is capable of receiving a variety of mechanical expressions, some of which, for the purpose of illustration, have been shown on the accompanying drawings. But it is to be expressly understood that the 60 drawings are for purposes of illustration only, and are not to be construed as definitions of the limits of the invention, reference being had to the appended claims for that purpose.

Referring to the drawings, wherein the same reference characters designate corresponding parts in the several figures,

Fig. 1 is a perspective elevation, partly in section, of an incased radiator so constructed as to provide a recess for the reception of the casing damper;

Fig. 2 is a vertical cross-section showing a radiator section in elevation;

Fig. 3 is an elevation of a radiator section having a rib so as to provide a partition in the casing;

Fig. 4 is a horizontal section, on line A—B, Fig. 3, of a portion of a radiator with its casing, showing the relation of the radiator 70 section illustrated in Fig. 3 to the casing;

Fig. 5 is a vertical section of a casing showing in elevation a modified radiator embodying the present invention;

Figs. 6 and 7 are details representing different arrangements of the radiator sections in the embodiment of Fig. 5.

Referring in detail to Figs. 1 and 2, 1 represents a radiator of any suitable construction for the employment of any desired 90 heating medium. 2 represents a casing for inclosing the same and 3 a grill in the upper portion of the front wall of said casing for permitting the escape of the heated air. 4 represents any suitable damper for regulating the flow of air through the casing, being shown as a plurality of shutters, and 5 designates any suitable means for operating the aforesaid shutters. In accordance with the present invention, the radiator is so constructed as to provide a recess for the reception of the damper, whereby the casing may closely embrace the radiator. While this recess may be provided at any suitable part of the radiator to accord with the position 95 of the damper, the illustrated embodiment shows the recess 6 as a reentrant space extending longitudinally of the radiator at the upper front edge thereof. As a convenient means for supporting the casing in 100 110

its position about the radiator, the latter may be provided with lugs 7, desirably cast integral with some of the radiator sections, as illustrated in Fig. 2, the casing resting on the upper faces of these lugs. It will be understood that the details of construction of the casing and damper may be of any suitable nature, as the same constitute no part of the present invention.

10 While the embodiment of the invention illustrated in Figs. 1 and 2 shows the radiator sections as each comprising a unitary, and preferably integral, plate-like piece so constructed as to provide a recess, the radiator sections may be built up of two or more parts, as illustrated in Figs. 5, 6 and 7, one part of each section being of a different height than the remainder of the section, whereby a reentrant space is provided.

15 20 In Figs. 5, 8 and 9 respectively designate two columns together constituting a section of a radiator, the column 8 being of less height than the column 9, whereby a reentrant space 10 is provided as shown for the reception of the shutters 4 of the damper. Where the radiator sections are made up of 25 two or more parts, as illustrated in Fig. 5, the parts may be disposed in alinement, as illustrated in Fig. 6, or in staggered relation, 30 as illustrated in Fig. 7. In this embodiment, the columns of the sections will have a common inlet and a common outlet. Referring to Figs. 6 and 7, a common inlet is shown as provided by the use of a T 11, connected by elbows 12 and 13 with the columns 8 and 35 9 respectively.

Referring to Figs. 3 and 4, if it is desired to provide a passage within the casing to obtain a predetermined circulation of air, such 40 a passage, for example, as disclosed in my aforesaid reissued Letters Patent wherein a passage in heat-interchanging relation with the radiator is employed to induce a circulation of air over a thermostat in a conduit communicating with said passage, a section of the radiator, as 14, may be provided with a rib 15, which may desirably be cast integrally with said section, said rib being of such dimensions as to engage the 45 inner faces of the wall or walls of the casing. The section 14, together with its rib, constitutes a partition within the casing, forming with the heat-insulating partition 16 a passage therein in heat-interchanging 50 relation with the radiator, through which passage the air will rise to cause a downflow of air through conduit 17 in communication with said passage. A suitable thermostat may be positioned in said conduit 17 55 for operating the damper, said thermostat being thereby subjected to a moving column of air at room-temperature, as fully explained and illustrated in my aforesaid reissued Letters-Patent to which reference is 60 made for a more detailed description.

While the illustrated embodiments have been described with considerable particularity, it is to be expressly understood that the invention is not to be restricted to the structures shown upon the drawings as the 70 same is capable of receiving a variety of mechanical expressions some of which will readily suggest themselves to those skilled in the art. Furthermore, it is to be expressly understood that, except as specified 75 in the claims hereto appended, this invention is not to be limited to any particular details of structure of the radiator and the casing.

What is claimed is:

1. The combination of a radiator and a casing therefor provided with a damper, said radiator being so constructed as to provide a recess for the reception of said damper. 80
2. The combination of a radiator and a casing therefor provided with a plurality of shutters constituting a damper, said radiator being so constructed as to provide a recess for the reception of said shutters. 85
3. The combination of a radiator and a casing closely embracing the same, said casing being provided with a damper, and said radiator being so constructed as to provide a recess for the reception of said damper. 90
4. The combination of a radiator and a casing closely embracing the same, said casing being provided with a plurality of shutters constituting a damper, and said radiator being so constructed as to provide a recess for the reception of said shutters. 100
5. The combination of a radiator and a casing therefor provided with a damper, said radiator being so constructed as to provide a reentrant space at one edge thereof for the reception of said damper. 105
6. The combination of a radiator and a casing therefor provided with a plurality of shutters constituting a damper, said radiator being so constructed as to provide a reentrant space at one edge thereof for the reception of said shutters. 110
7. The combination of a radiator and a casing closely embracing the same, said casing being provided with a damper, and said radiator being so constructed as to provide a reentrant space at one edge thereof for the reception of said damper. 115
8. The combination of a radiator and a casing closely embracing the same, said casing being provided with a plurality of shutters constituting a damper, and said radiator being so constructed as to provide a reentrant space at one edge thereof for the 120 reception of said shutters.
9. A radiator made up of integral plate-like sections so shaped as to provide a reentrant space extending longitudinally of the radiator at one edge thereof. 125

130

10. The combination of a radiator and a casing therefor, a section of said radiator being provided with a rib contacting said casing to constitute with said section of the 5 radiator a partition within said casing.
11. The combination of a radiator and a casing closely embracing the same, a section of said radiator being provided with a rib contacting said casing to constitute with 10 said section of the radiator a partition within said casing.
12. The combination of a radiator and a casing therefor provided with a damper, said radiator being so constructed as to provide 15 a recess for the reception of said damper, and a section of said radiator being provided with a rib contacting said casing to constitute with said section of the radiator a partition within said casing.
13. The combination of a radiator and a casing therefor provided with a damper, said radiator being so constructed as to provide a reentrant space at one edge thereof for the reception of said damper, and a section of said radiator being provided 20 with a rib contacting said casing to constitute with said section of the radiator a partition within said casing.
14. The combination of a radiator, a casing therefor provided with a damper, said radiator being so constructed as to provide 25 a recess for the reception of said damper, and lugs on said radiator upon which said casing rests.

In testimony whereof I have signed this 35
specification.

WESTON M. FULTON.
